(57) **CLAIM**

The ornamental design for a wire media storage rack, as shown and described.

DESCRIPTION

FIG. 1 is a front perspective view of one embodiment of the wire media storage rack of the present invention;

FIG. 2 is a front view of the wire media storage rack of FIG. 1;

FIG. 3 is a rear view of the wire media storage rack of FIG. 1;

FIG. 4 is a left side view of the wire media storage rack of FIG. 1, the right side view being a mirror image thereof;

FIG. 5 is a top view of the wire media storage rack of FIG. 1; and,

FIG. 6 is a bottom view of the wire media storage rack of FIG. 1.

The broken lines are for illustrative purposes only and form no part of the claimed design.
